UNITED STATES PATENT OFFICE.

SIDNEY B. WHITESIDE, OF NEW YORK, N. Y., ASSIGNOR TO THE POSTAGE STAMP SERVICE MACHINE COMPANY, OF SAME PLACE.

VENDING APPARATUS.

SPECIFICATION forming part of Letters Patent No. 465,908, dated December 29, 1891.

Application filed April 10, 1891. Serial No. 388,381. (No model.)

To all whom it may concern:

Be it known that I, SIDNEY B. WHITESIDE, a resident of the city, county, and State of New York, have invented an Improved Vending Apparatus, of which the following is a specification, reference being had to the accompanying drawings, forming a part thereof, wherein—

Figure 1 is a side elevation, partly in section, of my improved vending apparatus. Fig. 2 is a horizontal section on the plane of the line 2 2, Fig. 1. Fig. 3 is an enlarged vertical section of the interior mechanism of my apparatus on the plane of the line 3 3, Fig. 4. Fig. 4 is an enlarged horizontal section on line 4 4, Fig. 3. Fig. 5 is an enlarged vertical section on the line 5 5, Fig. 2. Fig. 6 is a vertical cross-section on the line 6 6, Fig. 7. Fig. 7 is a horizontal section on the line 7 7, Fig. 6. Fig. 8 is a vertical sectional view of a portion of my mechanism on the line 8 8, Fig. 4. Figs. 9 and 10 are cross-sections on the lines 9 9 and 10 10, Fig. 8. Fig. 11 is a top view of one of the stamp-containing cases, which may be used in my machine, and Fig. 12 is a bottom view of the reciprocating delivery-slide.

My invention relates to an improved machine for selling stamps, and distributing coins, packages, advertisements, or the like on the introduction of a suitable coin, and may be used in connection with a stamp-delivery apparatus of the kind described in my patent, No. 446,495, of February 17, 1891, and in my application for patent, bearing Serial No. 379,371, filed January 28, 1891; and it consists in the improved combination and arrangement of parts, hereinafter fully described.

The object of my invention is to construct a machine whereby stamps or the like may be sold, and at the same time the proper amount of change returned together with, if desired, a small advertisement in the shape of a card, disk, or the like, all to operate after the insertion of a coin of the proper denomination.

In the accompanying drawings, the letter A represents the outer casing of my improved machine, which is of any desired form, and which at any proper point may have the opening a, (see Fig. 1) for the introduction of a coin 2, which strikes against a lever C, causing it to move on its pivot b, thereby releas-

ing the mechanism by which the stamp and change are expelled, as hereinafter explained. The lever C has an arm d, which bears against a cam D, carried by the crank-shaft E. The lever C is hung on the pivot b, so that the end e, being the lightest end of the lever, is normally held in the raised position shown in Fig. 5, whereby a stop f on said lever will present itself in front of the cam D at the end 60 of every revolution of the shaft E. When the coin 2 is introduced into the slot a it falls against the end e of the lever C, thereby depressing the same and causing the stop f to retire from in front of the cam D. The shaft 65 E can then be revolved, thereby moving the cam D over the stop f and away from the arm d of the lever C. This allows the coin 2 to depress still farther the end e of the lever until the coin slips by said lever and falls 70 into a suitable tray or to the bottom of the case. The lever now drops back, or, should it not, the cam D by contact with the lever-arm d will force it back into the original position, and thereby bring the stop f again in 75 the track of the cam, checking the same until it is again released by the introduction of another coin. When the cam D is released, the shaft E may be rotated either by a handle B or any other suitable means. The 80 shaft E forms a cylindrical enlargement F recessed, as shown in Fig. 8, so that a pin G may be introduced from the end opposite the crank end of the shaft E and have two bearings g and h in said recessed enlargement. 85 This pin G is riveted or otherwise securely fastened to the frame i, that supports the inner mechanism, so that it will not rotate with the enlargement F. Upon this pin G is keyed another smaller flanged cylindrical body H, 90 as shown in Fig. 8. The object of this cylinder H is hereinafter explained.

Upon the shaft E is carried a gear-wheel I, which meshes with a gear-wheel J, carried on an arbor K, to which arbor is fixed a friction-roller M of rubber or analogous material. Adjacent to this roller M is another roller L, preferably of rubber, on an arbor Q. The arbors Q and K are geared together, as at p. 95

Directly below the stationary flanged cylinder or body H is placed a similar flanged roller N of substantially the shape of the cyl- 100

inder H. This roller is held in a suitable frame P and pressed upward by a spring R, Fig. 3, against the stationary body H. As the shaft E is revolved the thin part k of the 5 cylindrical enlargement F, which revolves around the stationary body H, passes between H and the roller N, depressing for a certain interval in every revolution and at the same time revolving the roller N. A 10 strip of stamps, preferably doubled together with a thin sheet of oiled paper interposed, has previously been placed in close proximity between the block H and roller N, as indicated by the letter S, Figs. 1, 2, 3, 4, 15 and 6. As the portion k of the shaft F passes between the block H and roller N, it depresses the roller N, and at the same time contacts with the stamps and forces them ahead toward the friction-rollers L and M until the part k of the shaft F ceases to depress the roller N, which then rises by the influence of the spring R and grips the strip of stamps 20 between it and the body H. Additional wires s s may be used, as shown in Figs. 3, 4, and 25 6, to insure a firmer grip upon the stamp. These wires when used are secured to the frame i and curved over the roller N and increase the stamps S. The stamps are now in the grasp of the rollers L and M, and a cutter 30 or knife T is then depressed by the action of cams m on shaft E, (see Figs. 4, 6, 8, and 9,) thereby cutting the stamp at the perforation. The knife T, as clearly shown in Fig. 4, is the central member of a U-shaped frame, which 35 is pivoted at n n to the frame i. One arm of this U-shaped cutter-frame extends beyond the pivot n and under a spring U, which keeps the knife in the elevated position (shown in Fig. 3) until the cams m depress the arms of 40 the cutter. The cutter in descending passes near the edge of a stationary platform t, on which the stamps rest, thereby facilitating the separation. The mechanism is previously adjusted, so that one rotation of the shaft E 45 will cause the stamps to move forward, in the manner above described, just one stamp's length, and the stamps are so placed between the rollers that when the knife T is depressed it cuts off the desired length. After the cutting, 50 the separated stamp or stamps will be moved forward by the rollers L M until they are discharged into the exterior tray V. At the time this occurs the remaining stamps in the machine stand still.

55 It will be seen that when the mechanism is ready for operation the end of the strip of stamps is directly under the cutting-blade T, which at that time is elevated. If at any time it is desirous to re-adjust the position of the 60 strip of stamps, a lever W, which may be easily accessible and which projects from or bears upon the roller-frame P, may be depressed, thereby separating the roller N and block H, and allowing the stamps to be freely moved 65 forward or backward. The wire guides s (see Figs. 3, 4, and 6) may be supplied to more readily assure the direction of the stamps

and to more firmly secure the stamps from being pulled between the rollers.

X is a gear-wheel carried by the shaft E, 70 preferably outside of the frame-work i. This gear-wheel meshes with another gear-wheel Y, which rotates the perforated disk Z. This disk Z takes and discharges from one or more tubes Z² coins or other packages or pasteboard disks, each containing, if desired, a printed advertisement, &c. I will not explain this feature in detail, as it is substantially what is described in my application, Serial No. 379,371, filed January 28, 1891. 80

What I do desire to further describe is another device in combination with what I have specified, whereby an additional package—for instance, a small metal case—which may contain stamps or the like, (see Fig. 11,) 85 will be discharged with every revolution of the shaft E. Directly above the disk Z are two upright tubes of any desired form A' A'. Below these is a bottom plate B', Fig. 6, which partially—preferably over half—closes the 90 opening of each tube. Above this bottom plate B' is a perforated slide D', Figs. 6, 7, and 12, which intervenes between the packages in each tube A' and the bottom plate B'. If the slide D' is reciprocated back the package contained in one of the tubes A' will enter the perforation in said slide and rest on the bottom plate B' until the slide is moved along and carries the package directly over the hole in the bottom plate B', whereupon the package drops into any suitable chute, and thence into the exterior tray V. Each stroke of the slide D' takes one package from one of the tubes A', and at the same time a package is also discharged from one of the tubes Z². The 95 slide D' is moved in the following manner: A wheel E' may be frictionally or by teeth at the edge rotated by the revolving disk Z. To the wheel E' is secured a crank-pin F', which is carried in a circle by the rotation of the wheel E' and which passes through a slot of the slide D', so that the circular movement of the pin is transformed into a rectilinear movement of the slide D', as can be readily understood. The shaft E should be supplied with 100 a ratchet-wheel H' and the frame i with the pawl h', which will prevent the shaft E from being turned in the wrong direction. The 105 stamps are fed from a spool I', Fig. 1, or may be put in the case, as shown by Fig. 11, thereby 110 doing away with the spool altogether. A slight tension may be supplied to the stamp-spool to prevent the uncalled for unrolling of the stamp-strip. This tension may be supplied by the spring i' bearing against the side 115 of the spool I', Fig. 1, or by the spring k' bearing against the strip of stamps. 120

Among the many advantages of my improved vending apparatus may be specified the following:

I am enabled by means of this apparatus to sell three different kinds of packages or merchandise at the same time—that is to say, one set of packages from the tubes Z², one

set from the tubes A', and one set from the spool I'; and I am also enabled, if I dispense with the spool, to sell simultaneously two different sets of packages from the tubes A' 5 and Z².

Another advantage is that when a spool is employed, the tension upon the strip of stamps can be relaxed for adjusting the strip in the feeding apparatus by the use of the lever W. 10 Other advantages respecting the character of the feed from the spool result from the employment of the recessed enlargement F of the shaft E, said recessed enlargement forming the feed portion k, which, when in contact 15 with the roller N, feeds the strip of stamps along, but which, when out of contact with the roller N, causes the block H to bear against the roller N, and thus prevents any feeding of the stamp at that time, permitting, however, 20 the detached portion of the stamp which was separated by the cutter to be fed along by the rollers L and M. The action of the knife T, being positive in manner described, is also superior to the use of a stationary detaching-blade, as has heretofore been suggested for such purposes in analogous machines. 25

Having now described my invention, what I claim, and desire to secure by Letters Patent, is—

1. In a vending apparatus, the combination of a tube or tubes Z², with the perforated disk Z below the same, and mechanism, substantially as described, for turning said disk, and 35 with the tube or tubes A', perforated slide D' below the same, and means for reciprocating said slide, all arranged substantially as herein shown and described.

2. The combination, in a vending apparatus, of the tube or tubes Z², the perforated disk Z below the same, tube or tubes A', perforated slide D', below the same, and stamp-spool I', and means, substantially as described, for feeding the stamps from said spool, all arranged for delivering merchandise from each 45 of said three receptacles, as specified.

3. The combination of the tube or tubes Z², perforated disk Z, tube or tubes A', perforated slide D', toothed-wheel E', having crank-50 pin F' and gearing with the disk Z, and means, substantially as described, for turning said disk, all as specified.

4. In a vending apparatus, the combination of the lever C, having cam-stop f, and arm d, 55 with the crank-shaft E, having cam D, adapted to be located between the stop f and the arm d, and with the coin-chute a, all arranged so that the contact of the cam D with the arm d shall raise the coin-receiving end of said lever, substantially as herein shown and described.

5. The combination of the reel I', with the

spring-pressed roller N in its movable frame P, with the shaft E, having recessed portion F, and fixed pin G, carrying block H, a thin 65 portion k of the recessed portion F of the shaft E being in alignment with the stationary block H, substantially as and for the purpose herein shown and described.

6. The combination of the feed-roller N and 70 rotating counter-feed piece K, adapted to bear upon the roller N, with the frame P, in which the roller N has its bearing, spring R, and with the lever W for depressing the roller N, substantially as herein shown and described. 75

7. The combination of the reel I' and suitable feed-rollers N and F, with the U-shaped cutter-frame T, whose central member constitutes a cutter in front of said feed-rollers, and with the shaft E, having cam m for depressing said cutter-frame and spring N for raising it, all arranged substantially as described. 80

8. The combination of the reel I' and suitable feed-rollers N and F, with the U-shaped 85 cutter-frame T, whose central member constitutes a cutter in front of said feed-rollers, and with the shaft E, having cam m for depressing said cutter-frame and spring U for raising it, and with the outer feed-rollers L 90 and M, substantially as herein shown and described.

9. The combination of the shaft E, having toothed-wheel I and recessed portion F, with feed-piece k thereon, and stationary spindle 95 G, carrying stationary block H, with the spring-pressed feed-roller N, U-shaped cutter-frame T, and means, substantially as described, for raising and lowering the same, and with the feed-rollers L M and with the toothed wheel J on the feed-roller M, all substantially as herein shown and described. 100

10. The combination of the shaft E, having recessed portion F and forming the feed-surface k, with the stationary pin G, stationary 105 block H, spring-pressed feed-roller N, and with the curved wires s s, all arranged for operation substantially as herein shown and described.

11. The combination, in a stamp-vending 110 apparatus, of the actuating-shaft E, and means, substantially as described, for throwing the same into action by the introduction of the coin with the stamp-reel I', means, substantially as described, for feeding the stamp-strip forward and unwinding it from said reel, and with the cam-actuated cutter-frame T and the outer feed-rollers L M, substantially as 115 herein shown and described.

SIDNEY B. WHITESIDE.
